8 Claims. (Cl. 77—58)

This invention relates to cutting, more particularly this invention relates to cutting tools and apparatus combinations including cutting tools, and pertains more particularly to tools and apparatus for use on metal and other materials for internal cutting and/or undercutting which can be conveniently and easily adjusted to cut various shapes and sizes of cuts. Still more specifically, this invention relates to a rotary tool having a slidable bit holder and a means to accurately and automatically correlate the movement of the bit holder as the tool is rotated relative to the work.

In industry, there is a constant need for internal cutting and undercutting of metals and other materials. A specific example illustrating this need is a self-aligning bearing mount wherein a bearing element having a truncated spherical exterior surface on its outer race is seated in a mounting block or mounting ring having an aperture receiving the bearing element provided with a complementary internal truncated spherical surface. A bearing so mounted is free to pivot, relative to the bearing block or ring, a limited amount sufficient to align itself with a shaft received in the bearing. This type of mounting is very desirable since it saves the relatively high cost of aligning perfectly the bearing mounts for a shaft, and is also sufficiently flexible to allow subsequently automatic aligning of the supporting bearings in the event of a shifting or distortion of portions of the apparatus having the bearing mounts mounted thereon. In addition to this one example, there are many other instances where it is desirable to make an internal cut and/or undercut in an existing aperture in work.

Accurate internal cutting and undercutting of materials is ordinarily quite an expensive operation. An operation involving an undercut is often produced on a lathe provided with a shaped cutting tool having the desired profile shape of the cut which is moved radially against the work as it is rotated. This method is expensive and has many disadvantages and limitations. If the work is done accurately, it must necessarily be performed by a skilled machinist. The operation is slow and tedious necessitating precise and time consuming feed and work mounting operations and is not well adapted to production line methods. The equipment used to make a cut is also quite expensive. The shaping tool referred to hereinbefore is expensive to make and cannot be adjusted for other variations of shapes. Further, this method of cutting is not practical, if the work is very large, since it must be mounted on a turntable or the like. Another more recent method of producing undercuts in work is through the use of a lathe provided with a "tracing" apparatus. This method is in general quite expensive and involves mounting the work. The equipment used for this purpose is also very expensive. A tracer lathe costs from \$7,000 to \$25,000 depending on size, etc. In short, there is a pressing need for a simple convenient and inexpensive cutting tool apparatus embodying same for producing accurate undercuts which is adaptable to frequent modification and size changes. The

2

apparatus used and known to the prior art before the disclosure of our new drill bit or boring bar and a combination apparatus have not been satisfactory to fulfill this pressing need.

5 Our invention is a rotary cutting tool having a body, a bit holder slidably mounted in the body and a cutting edge carried on the bit border. Also, provided is a mechanism that will accurately and positively correlate the movement of the bit holder relative to the body with the relative position of the body to the material being worked upon. Preferably, the body has a transverse bore with the bit holder slidably mounted therein. The mechanism used to correlate the movement of the bit holder is desirably a spring loaded plunger provided with a cam follower engaging a cam means mounted on the bit holder.

10 The apparatus combination for internal cutting of our invention has a work support, a tool support, a means to rotate and longitudinally move the tool support relative to the work support, and a cutting tool mounted on the tool support. The cutting tool has a body, a bit holder 20 slidably mounted on the body, a cutting edge carried on the bit holder, and a mechanism which will positively and accurately correlate the movement of the bit holder relative to the body with the relative position of the body to the material being worked upon. Preferably, the apparatus combination includes an abutment means on the work support consisting of a bearing having an inner roll. The correlating mechanism is preferably a longitudinally 25 slidable spring loaded plunger having a cam follower engaging a cam mounted on the bit holder. Movement of the plunger relative to the body causes movement of the bit holder.

25 The apparatus and cutting bit of our invention solves all of the problems relating to internal cutting and/or undercutting of materials, and in particular metals, known to the prior art. The apparatus combination for internal cutting and the cutting tool of our invention can be operated by relatively unskilled persons. Work can be produced by such persons having very close tolerances. Tolerances of $\frac{1}{1000}$ of an inch are readily obtainable. The cutting bit can be adjusted simply and quickly to very close tolerances while it is mounted and assembled on the apparatus. There is no necessity for completely disassembling the cutting tool to make either a minute or a major 30 adjustment in the position of the cutting bit relative to the cutting tool. Further the profile shape of the cut in the work can be readily changed by simply and quickly replacing the cam element. The apparatus and drill bit of our invention is relatively inexpensive. The cutting 35 bit can be used with any suitable type of conventional machine apparatus having a means to mount the tool and rotate either the tool or the work. After the work is finished the machine can be converted to other operations by simply removing the cutting bit. The cutting tool 40 is relatively inexpensive and can be used to produce a variety of types of cuts having different profiles by using different shaped cam elements. These cam elements for use in our cutting bit of our invention can be easily, quickly and inexpensively produced having close tolerances. The aforementioned features make the apparatus and cutting tool of our invention readily adaptable to mass 45 production techniques.

50 The apparatus and cutting tool of our invention solves the problems associated with internal cutting and undercutting known to the prior art by eliminating the need of

a skilled operator to operate the apparatus producing the cut. It also materially reduces the cost of the machine and tools necessary to produce this type of work. In addition, changeovers from one type of internal cut to another are greatly simplified by the design and structure of our cutting tool. Adjustments to the cutting tool proper of our invention are very simple and can be executed by relatively unskilled personnel.

It is an object of this invention to provide a new apparatus combination for working materials, work such as machining and cutting.

It is another object of this invention to provide a cutting tool adapted for working materials, work such as machining and cutting.

Still another object of this invention is to provide a relatively inexpensive apparatus combination that can be used to produce accurate internal cuts and undercuts that can be operated by relatively unskilled personnel.

Yet another object of this invention is to provide a cutting tool for undercutting and internal cutting that can be used by relatively unskilled personnel.

Another object of this invention is to provide a cutting tool that can be easily and simply adjusted without disassembling same.

Another object of this invention is to provide a cutting tool which can be used to produce cuts, etc., having different profiles.

Yet another object of this invention is to provide a cutting tool adapted for internal cutting and undercutting which can be changed to automatically produce different cuts having different profiles by merely changing a cam element.

Yet another object of this invention is to provide an apparatus combination and/or cutting tool that is particularly adapted for mass production techniques.

Another object of this invention is to provide a new cutting tool that will automatically produce with very great accuracy internal cuts and/or undercuts in materials.

Yet another object of this invention is to provide a cutting tool wherein the cutting bit can be quickly and easily removed and replaced and/or adjusted without disassembling the cutting tool.

Other objects and advantages of the invention will be apparent to those skilled in the art from the disclosure set forth herein.

Drawings of preferred specific embodiments of the invention accompany and are a part hereof, and such are to be understood to not unduly limit the scope of the invention. In the drawings,

FIG. 1 is a front elevational view in cross section of the new cutting tool of our invention.

FIG. 2 is a side elevational view of same.

FIG. 3 is a sectional view taken on line 3—3 of FIG. 1.

FIG. 4 is a sectional view taken on line 4—4 of FIG. 1.

FIG. 5 is a sectional view taken on line 5—5 of FIG. 1.

FIG. 6 is a sectional view taken on line 6—6 of FIG. 1.

FIG. 7 is a front elevational view illustrating an embodiment of the apparatus combination for internal and/or undercutting of our invention.

FIG. 8 is an enlarged view in cross section illustrating the cutting tool and its relation to work being operated on, secured to a work support.

The following is a discussion and description of the new apparatus combination and cutting tool sub-combination of our invention made with reference to the drawings, whereon the same reference numerals are used to indicate the same or similar parts and/or structure. The discussion and description are of preferred specific embodiments of the new apparatus combination and cutting tool sub-combination of our invention, and it is to be understood that such is not to unduly limit the scope of our invention.

Referring now to the drawings FIGS. 1-8 and FIGS. 1-6 in particular, cutting tool 10, a preferred specific embodiment of our invention is illustrated. Cutting tool 10

is a rotary metal cutting tool for cutting an internal cut or undercut on the surface of an aperture or the like. Cutting tool 10 has an elongated body having a shank portion 12 on the first upper end. The shank 12 is shown provided with a flat surface 14 machined in the cylindrical portion thereof and is adapted to be engaged by a set screw or the like associated with a conventional tool holding means. The tool shank 12 can be altered in shape to fit any type tool securing means. For example, it can be given a tapered shape as is well known in the art. The body 11 has an enlarged cylindrical intermediate portion 16 and a reduced cylindrical guide portion 18 on the lower end opposite the shank 12. The intermediate portion of the cutting tool can be given any suitable shape. In the preferred specific embodiment illustrated in the drawings, the intermediate portion 16 has an upper portion which is slightly enlarged. The body 11 of the drill cutting tool can be made of any suitable type of material. Preferably, the body 11 is made of an alloy steel, for example number 4130 or 4340. A longitudinally extending first groove 20 having a semi-circular transverse cross section is disposed in the guide portion 18 extending the entire distance thereof. A first longitudinally extending circular bore 22 is disposed in the intermediate portion 16 and is aligned with groove 20 in the guide portion 18. The groove 20 and bore 22 have the same radius of curvature. If desired, the groove and bore can be given any other suitable type of configuration. A relatively large transversely extending second bore 24 is provided in the intermediate portion 16 and positioned so that its axis intersects the axis of bore 22. A cylindrical shaped bit holder 26 is slidably disposed in bore 24. The bore 24 and bit holder 26 can be given any suitable cross sectional shape as for example, square, hexagonal, etc.

The cylindrically shaped bit holder 26 is provided with curved end surfaces that have the same radius of curvature as the radius of curvature of the cylindrical surface of intermediate portion 16. When the bit holder 26 is disposed in the body 11, its end surfaces are complementary to the exterior surface of intermediate portion 16. As shown in FIG. 4, bit holder 26 is provided with a first transverse aperture 28 which aperture has an elongated or oblong cross section. The aperture 28 is positioned adjacent a first end 29 of bit holder 26. When the bit holder is in position in the intermediate portion 16 of the cutting tool, aperture 28 communicates or is in line with bore 22. As is shown in FIG. 4, aperture 28 communicates with bore 22 when bit holder 26 is moved back or forth. A second small longitudinally extending groove 30 is disposed parallel to aperture 28 in bit holder 26. A cam means 32 is mounted in second groove 30 and consists of a flat element having a thickness equal to the thickness of groove 30 and having an arcuate shaped camming surface 34 which is identical to the profile or cross sectional shape of the spherical shape to be cut in the work. The cam element 32 can be given any suitable shape which shape determines the type and profile of the cut produced in the work. Cam element 32 can be made of any suitable type of material, and is preferably formed of high speed steel. Two spaced transverse holes are provided in the bit holder 26 which extend through groove 30. Two roll pins, or dowel pins 36, are frictionally engaged in the aforementioned spaced holes and extend through the cam means 32 to secure same in secured relationship to the bit holder 26. The cam means can be removed from the bit holder 26 by merely removing the dowel pins 36 from the holes thus releasing same. The longitudinally extending central aperture 38 is provided in the second opposite end 40 of bit holder 26. A tool bit 42 having an end cutting edge 44 is disposed in aperture 38 and protrudes from same. A transverse threaded aperture 46 intersects the central aperture 38. Bolt means 48 is threadedly engaged in aperture 46 to adjustably and releasably secure the tool bit 42 in operative position in bit holder 26. An access aperture 50 is provided in the intermediate portion 16 that

is aligned with the last-mentioned threaded aperture 46. Access aperture 50 allows a suitable tool to be inserted therethrough to engage bolt 48 to release or adjust the position of cutting bit 42 while the cutting tool is in assembled position.

A means is provided to longitudinally adjust the position of the cutting bit 42 in the bit holder 26. This means is clearly shown in FIG. 4 and consists of a diagonal extending aperture 52 which intersects the axis of central aperture 38, a pin means 54 disposed in the diagonal aperture 52 which contacts with one end and end of the cutting bit 42, and a longitudinally extending threaded aperture 56 intersecting the diagonal aperture 52. A bolt means 58 is threadedly engaged in the threaded aperture 56 and contacts the opposite end of the pin means 54 in position in the diagonal aperture. By turning bolt 58, it is thereby possible to move cutting bit 42 relative to cutting bit 26. Movement of bolt 58 contacts and moves pin 54 which in turn urges cutting bit 42.

A spring loaded retaining means is provided for urging the bit holder 26 in a retracted position relative to the cutting bit. The retaining means consists of a closed end longitudinally extending third groove 60 in the outer surface of bit holder 26, a helical spring 62 disposed in the groove 60 and slidable abutment means 64 positioned at one end of spring 62. A transverse threaded aperture 66 is provided in the intermediate portion 16 which intersects the second bore 24. A bolt means 68 threadedly engaged in aperture 66, having a portion 69 extending between abutment means 64 and the end of groove 60, thus secures the bit holder 26 within the second bore. The spring 62 acts to constantly urge the bit holder in a retracted position relative to the cutting tool. This position is clearly shown in FIG. 4 of the drawings.

A camming plunger 70 is slidably disposed in first groove 20 in the guide portion 18 and first bore 22 in the intermediate portion 16 and extends through the first transverse aperture 28 in bit holder 26. This relationship is shown in FIG. 1. The camming plunger 70 has a longitudinally extending fourth groove 72 provided therein which is adapted to slidably receive the cam means 30 of bit holder 26. A pointed cam follower means 74 is provided in fourth groove 72 and adapted to operatively engage the arcuate surface 34 of cam means 32. The cam follower is preferably made of a very hard material, most preferably hardened steel. In the embodiment illustrated it is a transverse pin, inserted through apertures spaced from the bottom of the groove 72. A backing means is preferably provided for the cam follower pin consisting of material 75 disposed back of and supporting pin 72. The groove is deeper on each side of the cam follower to receive the cam 32, as shown in FIG. 1. It can be seen that reciprocation of camming plunger 70 within the groove and bore mentioned hereinbefore causes transverse sliding movement of the bit holder 26 when cam follower means 74 engages the camming surface 34 of cam 32. If the profile of the cut produced by cutting bit 42 is desired to be arcuate in form, a cam having an arcuate camming surface must be provided. It can be seen that any type profile cut can be produced by merely interchanging cam 32 for a suitable shaped cam. A locking means for said camming plunger 70 is provided. A locking means is desirable in order to lock the cutting bit 42 in a retracted position when the tool bit is taken or removed from the aperture. This prevents breaking or chipping of the cutting edge and possible scratching of the work. The locking means for the camming plunger consists of a transverse aperture 76 in the camming plunger adjacent the end thereof and an aperture 78 in the intermediate body portion 16 intersecting the first bore 22 in a line with the last-mentioned transverse aperture 76 when said camming plunger is in a depressed position. A second helical spring means 80 is disposed in first bore 22 positioned longitudinally of the camming plunger 70 which urges it outwardly into an extended position. An

75

oil hole 82 is provided to facilitate lubricating the plunger 70 and its associated adjacent elements. Plunger 70 is provided with a means to vary the length between the lower abutting end surface and the cam follower 74. The means consist of a threaded portion 83 on the lower portion of rod 70, an internally threaded tip element 84, and an exteriorly thread locking plug 85. In use the plug 85 is loosened, tip 84 adjusted to the desired position, and the plug retightened.

10 A longitudinally extending chip receiving groove 90 is provided in the intermediate portion 16 of cutting bit 10 and also on the second end face 40 of bit holder 26. The chip receiving groove 90 aids in the orderly removal of the metal removed from the work by the cutting bit 10. 15 The cutting tool 10 is adapted when rotated relative to a work piece having an aperture and an abutment race to cut a truncated spherical surface on the inside surface of the aperture.

In FIG. 7 is shown a specific embodiment of my apparatus combination 100. The apparatus combination 100 is a vertical milling machine or drill press having a work support 102, a tool support 104, and a means 106 to rotate and longitudinally move the work support relative to the tool support. As shown in FIG. 8, an 20 abutment surface 108 is provided on the work support 102. The abutment surface 108 is provided by bearing element 107 having an outer race 110 securely fixed to the work support 102 and an inner race 112 aligned with the tool support 104. The inner race 112 serves as an 25 abutment means for the camming plunger 70 and also has a guiding element to receive and guide the guide portion 18 of the cutting tool 10. The cutting tool 10 is shown mounted in the tool support 104 and is of the 30 construction described hereinbefore. The specific embodiment of the work support shown in FIG. 8 includes a spacing plate 114 secured to the table with bolts 116. Two of the bolts are stub bolts 118 without a head element. This arrangement facilitates the removal of the 35 spacing element 114 since only two of the four bolts must be removed in order to disassemble same. The work 40 120 having an aperture 122 is shown mounted on spacing plate 114. As illustrated in FIG. 8, the cutting tool 10 has completed approximately one-half of the cut required 45 to form a truncated spherical surface in the work 120. As illustrated, the cam follower 74 contacts the surface 34 of cam 32 in approximately the center thereof, the drill press is shown provided with a work support 102 having a plurality of locations where work elements can be 50 accurately located and subsequently moved to a position under and aligned with the tool support 104. A suitable carriage 125 provides the means to change position.

In operation, the cutting tool 10 is rotated and moved longitudinally through an aperture 122 of work 120. As the cutting tool 10 reaches a point where the lower end 55 84 of camming plunger 70 contacts the abutment surface 108, the cam abutment follower 74 and cam surface 34 cooperate to urge the cutting tool 42 into the work 120. It can be seen that the profile of the cut produced in the work can be varied by merely changing the camming surface 34 on cam 32. When the cutting element has 60 proceeded completely through the work 120, the plunger 70 is completely depressed. In this position, aperture 78 is aligned with aperture 76. Any suitable tool can be inserted into the aligned apertures to thus hold the plunger 70 in a retracted depressed position which in turn maintains the cutting tool in a retracted position which can 65 then be conveniently removed from the work without scratching the work or breaking or chipping the cutting edge.

While I have described and illustrated preferred specific 70 embodiments of our invention, it is to be understood that the apparatus combination and cutting tool disclosed can be made in other forms than herein described or suggested without departing from the spirit of our invention.

We claim:

1. A rotary metal cutting tool for cutting an internal

truncated spherical surface comprising, an elongated body having a shank portion on a first end, an enlarged cylindrical intermediate portion, and a reduced cylindrical guide portion on the opposite second end, a longitudinally extending first groove having a semi-circular transverse cross section disposed in said guide portion extending the entire distance thereof, a first longitudinally extending circular bore in said intermediate portion aligned with said first groove in said guide portion, a relatively large transversely extending second bore in said intermediate portion positioned so that its axis intersects the axis of said first bore, a cylindrically shaped bit holder slidably disposed in said second bore, a first transverse aperture having an elongated cross section in said bit holder adjacent a first end portion thereof, said first aperture communicating with said first bore when said bit holder is in operative position, a second small longitudinally extending groove in said first transverse aperture, a cam means mounted in said second groove, said cam means comprised of a flat element having a thickness equal to the thickness of said second groove and having an arcuate shaped camming surface identical to the profile of the spherical shape to be cut protruding from said second groove, a pin means passing through said cam means and into said bit holder removably securing said cam means, a longitudinally extending central aperture in the second opposite end of said bit holder, a tool bit having an end cutting edge disposed in said central aperture and protruding from same, a transverse threaded aperture intersecting said central aperture, a bolt means in said last-mentioned threaded aperture for adjustably and releasably securing said tool bit in operative position, a means to longitudinally adjust the position of said cutting bit in said bit holder, a spring loaded retracting means for said bit holder comprising, a closed end longitudinally extending third groove in the outer surface of said bit holder, a helical spring longitudinally disposed in said third groove, a slideable abutment means in said third groove positioned at one end of said spring, a transverse threaded aperture in said intermediate portion intersecting said second bore, and a bolt means threadedly engaged in said last-mentioned threaded aperture having a protruding portion extending between said abutment means and the end of said third groove to releasably secure said bit holder within said second bore, a camming plunger slidably disposed in said first groove in said guide portion and said first bore in said intermediate portion and extending through said first transverse aperture in said bit holder, a longitudinally extending fourth groove in said camming plunger adapted to slidably receive said cam means on said bit holder, a pointed transverse cam follower means in said fourth groove adapted to operatively engage the arcuate surface of said cam means, a locking means for said camming plunger in a depressed position, a second helical spring means in said first bore positioned longitudinally of said camming plunger urging same outwardly in an extended position, said cutting tool adapted when rotated and moved longitudinally relative to a work piece having an aperture, and an abutment race, to cut a truncated spherical surface on the inside surface of the aperture thereof.

2. A rotary cutting tool for internal cutting comprising, an elongated body having a shank portion, an enlarged cylindrical intermediate portion, and a reduced cylindrical guide portion, a longitudinally extending first groove disposed in said guide portion extending the entire distance thereof, a first longitudinally extending bore in said intermediate portion aligned with said first groove in said guide portion, a relatively large transversely extending second bore in said intermediate portion intersecting the axis of said first bore, a bit holder slidably disposed in said second bore, a first transverse aperture having an elongated cross section in said bit holder adjacent a first end thereof, said first aperture communicating with said first bore when said bit holder is in operative position, a

second small longitudinally extending groove in said first transverse aperture, a cam means removably mounted in said second groove, said cam means having a camming surface identical to the profile of the desired shape of the cut to be produced protruding from said second groove, a longitudinally extending central aperture in the second opposite end of said bit holder, a tool bit having a cutting edge removably mounted in said central aperture and protruding from same, a means to longitudinally adjust the position of said cutting bit in said bit holder, a spring loaded retracting means for said bit holder comprising, a closed end longitudinally extending third groove in the bit holder, a spring means disposed in said third groove, a protrusion means on said intermediate portion abutting an end of said spring means in said third groove to thereby secure said bit holder within said second bore, a camming plunger slidably disposed in said first groove in said guide portion and said first bore in said intermediate portion and extending through said first transverse aperture in said bit holder, a longitudinally extending fourth groove disposed in said camming plunger and adapted to slidably receive said cam means on said bit holder, a cam follower means in said fourth groove adapted to operatively engage the cam means, a locking means for said camming plunger in a depressed position, a spring means in said first bore for urging said camming plunger outwardly in an extended position, said cutting tool adapted when rotated and moved longitudinally relative to work having an aperture, and relative to an abutment race, to produce an internal cut on the inside surface of said aperture thereof.

3. A cutting tool for internal cutting comprising, an elongated body having an intermediate portion, and a reduced cylindrical guide portion, a first longitudinally extending bore in said intermediate portion, a relatively large transversely extending second bore in said intermediate portion positioned so that its axis intersects the axis of said first bore, a bit holder slidably disposed in said second bore, a first transverse aperture in said bit holder, said first aperture communicating with said first bore when said bit holder is in operative position, a cam means mounted within said first transverse aperture in said bit holder, said cam means comprised of a flat element having a camming surface corresponding to the profile of the desired cut to be produced, a tool bit having a cutting edge mounted on said bit holder, means to adjustably and releasably secure said tool bit on said bit holder, a means to longitudinally adjust the position of the cutting bit relative to said bit holder while said bit holder is in assembled position in said second bore, a spring loaded securing and retracting means for said bit holder, a camming plunger slidably disposed in said first bore in said intermediate portion and extending through said first transverse aperture in said bit holder, a longitudinally extending fourth groove in said camming plunger adapted to slidably receive said cam means on said bit holder, a cam follower means in said fourth groove adapted to operatively engage the cam surface of said cam means, a means to lock said cam plunger in retracted position, a spring means for urging said plunger in extended position, said cutting tool adapted when rotated relative to the work to make an accurate internal cut, the shape of said cut being controlled by the shape of the camming means positioned in said bit holder.

4. A rotary cutting tool for internal cutting comprising, a body, an enlarged intermediate portion on said body, a reduced guide portion on said body, a first longitudinally extending bore in said intermediate portion, a transversely extending second bore in said intermediate portion positioned so that its axis intersects the axis of said first bore, a bit holder slidably disposed in said second bore, a transverse aperture in said bit holder, said last-mentioned aperture communicating with said first bore when said bit holder is in operative position within said second bore, a cam means having a camming surface secured within said transverse aperture in said bit holder, a tool bit hav-

ing a cutting edge mounted on said bit holder, a means for adjustably and releasably securing said tool bit to said bit holder, a means for adjusting said bit holder relative to said intermediate portion, a camming plunger slidably disposed in said first bore in said intermediate portion and extending through said transverse aperture in said bit holder, a cam follower means on said camming plunger adapted to operatively engage the camming surface of said cam means, said cutting tool adapted to make an internal cut.

5. An apparatus combination for undercutting, comprising, a drill press, said drill press having a rotatable and longitudinally movable spindle, tool attachment means on said spindle, a work support means arranged opposite and in spaced relation to said spindle, a bearing means having an internal race mounted on said work support and aligned with said spindle, a work securing means on said work support, a cutting tool secured to said spindle comprising, an elongated body having a shank portion, an enlarged cylindrical intermediate portion, and a reduced cylindrical guide portion, a longitudinally extending first groove disposed in said guide portion extending the entire distance thereof, a first longitudinally extending bore in said intermediate portion aligned with said first groove in said guide portion, a relatively large transversely extending second bore in said intermediate portion intersecting the axis of said first bore, a bit holder slidably disposed in said second bore, a first transverse aperture having an elongated cross section in said bit holder adjacent a first end thereof, said first aperture communicating with said first bore when said bit holder is in operative position, a second longitudinally extending groove in said first transverse aperture, a cam means removably mounted in said second groove, said cam means having a camming surface identical to the profile of the desired shape of the cut to be produced in the work protruding from said second groove, a longitudinally extending central aperture in the second opposite end of said bit holder, a tool bit having a cutting edge removably mounted in said central aperture and protruding from same, means to longitudinally adjust the position of said cutting bit in said bit holder, a spring loaded retracting means for said bit holder comprising, a closed end longitudinally extending third groove in the bit holder, spring means disposed in said third groove, protrusion means on said intermediate portion abutting an end of said spring means in said third groove to thereby secure said bit holder within said second bore, a camming plunger slidably disposed in said first groove in said guide portions and said first bore in said intermediate portion and extending through said first transverse aperture in said bit holder, a longitudinally extending fourth groove disposed in said camming plunger and adapted to slidably receive said cam means on said bit holder, a cam follower in said fourth groove adapted to operatively engage the cam means, a locking means for said camming plunger in a depressed position, spring means in said first bore for urging said camming plunger outwardly in an extended position, said apparatus combination when in use having said cylindrical guide portion engaged within said inner race of the bearing means mounted on said work support and with the lower end of said camming plunger engaging the upper radial face of said inner face allowing the body of the cutting tool to be moved longitudinally as it is being rotated to thereby correlate the transverse movement of the cutting bit with the longitudinal movement of the tool body to thereby make the desired internal cut.

6. An apparatus combination for internal cutting comprising, a work support, a tool support, a means to rotate and longitudinally move said work support relative to said tool support, abutment means on said work support, and a cutting tool mounted on said tool support, comprising, a body, an enlarged intermediate portion on said body, a reduced guide portion on said body, a

first longitudinally extending bore in said intermediate portion, a transversely extending second bore in said intermediate portion positioned so that its axis intersects the axis of said first bore, a bit holder slidably disposed in said second bore, a transverse aperture in said bit holder, said last-mentioned aperture communicating with said first bore when said bit holder is in operative position within said second bore, a cam means having a camming surface secured within said transverse aperture in said bit holder, a tool bit having a cutting edge mounted on said bit holder, a means for adjustably and releasably securing said tool bit to said bit holder, means for retaining and retracting said bit holder relative to said intermediate portion, a camming plunger slidably disposed in said first bore in said intermediate portion and extending through said transverse aperture in said bit holder, a cam follower means on said camming plunger adapted to operatively engage said camming surface of said cam means, said apparatus constructed and adapted when in use with said camming plunger engaging said follower means of said work support as the cutting tool is rotated and moved longitudinally relative to the work support, to correlate the transverse movement of said bit holder relative to said body of said tool with the longitudinal movement of said body, to thereby make the desired internal cut on work being worked upon.

7. A rotary cutting tool for internal cutting comprising, a body, a first longitudinally extending bore in said body, a transversely extending second bore in said body positioned so that its axis intersects the axis of said first bore, cutting means having a bit with a cutting edge and a shank slidably disposed in said second bore, a transverse aperture in said shank having an axis parallel to that of said first bore, said last-named aperture communicating with said first bore when said shank is in operative position within said second bore, said transverse aperture in said shank having an arcuate camming surface, a means for positionably adjusting said cutting means relative to said body, a camming plunger slidably disposed in said first bore in said body and extending through said transverse aperture in said shank, a cam follower means having an arcuate camming surface on said camming plunger adapted to operatively engage said arcuate camming surface of said transverse aperture in said shank, said cutting tool adapted to make an internal cut.

8. An apparatus combination for internal cutting comprising, a work support, a tool support, a means to rotate and longitudinally move said work support relative to said tool support, and a cutting tool mounted on said tool support, comprising, a body, a first longitudinally extending bore in said body, a transversely extending second bore in said body positioned so that its axis intersects the axis of said bore, cutting means having a bit with a cutting edge and a shank slidably disposed in said second bore, 55 a transverse aperture in said shank having an axis parallel to that of said first bore, said last-named aperture communicating with said first bore when said shank is in operative position within said second bore, said transverse aperture in said shank having an arcuate camming surface, means for positionably adjusting said cutting means relative to said body, a camming plunger slidably disposed in said first bore in said body and extending through said transverse aperture in said shank, a cam follower means having an arcuate camming surface on said camming plunger adapted to operatively engage said arcuate camming surface of said transverse aperture on said shank, said apparatus combination in use constructed and adapted to rotate said tool relative to work supported on said work support, with said camming plunger in contact with said work support adjusting the radial position of said cutting means in operative cooperation with said camming surface of said shank of said cutting means as the body of said tool is moved longitudinally relative to the work to produce an internal cut.
